(57) **CLAIM**

The ornamental design for a synchronization and charge hub, as shown and described.

DESCRIPTION

FIG. 1 is a top view of a synchronization and charge hub showing the new design, in a first embodiment;

FIG. 2 is a rear view thereof;

FIG. 3 is a bottom view thereof;

FIG. 4 is a front view thereof;

FIG. 5 is left side view thereof;

FIG. 6 is an open perspective view thereof;

FIG. 7 is a closed perspective view thereof; and,

FIG. 8 is right side view thereof.

1 Claim, 8 Drawing Sheets

FIG. 1

FIG. 2

FIG. 3

FIG. 4

FIG. 5

FIG. 7

FIG. 8
